DISPLAY COVER FOR AN AQUARIUM OR
SIMILAR ARTICLE

Richard N. Burnley, 116 University Place,
New York, N.Y. 10003

Filed Feb. 28, 1972, Ser. No. 230,191

Term of patent 7 years

Int. Cl. D30—02

U.S. Cl. D30—12

FIG. 1.

FIG. 2.

FIG. 3.

FIG. 4.

FIG. 5.

FIG. 1 is an isometric view of a display cover for an aquarium or similar article, showing my new design;

FIG. 2 is a top plan view;

FIG. 3 is a bottom plan view;

FIG. 4 is a front elevational view, the rear being the same; and

FIG. 5 is a side elevational view, the opposite side being the same.

I claim:

The ornamental design for a display cover for an aquarium or similar article, substantially as shown and described.
